UNITED STATES PATENT OFFICE.

WILLIAM A. DOBLE, OF SAN FRANCISCO, CALIFORNIA, ASSIGNOR TO THE PELTON WATER WHEEL COMPANY, OF SAN FRANCISCO, CALIFORNIA, A CORPORATION OF CALIFORNIA.

TURBINE-PUMP.

1,135,364.

Specification of Letters Patent. Patented Apr. 13, 1915.

Application filed June 2, 1913. Serial No. 771,306.

To all whom it may concern:

Be it known that I, WILLIAM A. DOBLE, a citizen of the United States, and resident of San Francisco, county of San Francisco, 5 State of California, have invented certain new and useful Improvements in Turbine-Pumps, of which the following is a specification.

This invention relates to turbine pumps and has for its object the construction of the 10 pump casing in such a manner that all of the water passages are readily accessible for the purpose of machining during the construction of the pump and also for the purpose of cleaning the passages when they become obstructed. In this class of pumps the 15 velocity of the water is very high and it is therefore of great importance to have all of the passages as smooth as possible in 20 order to reduce the frictional losses to a minimum.

The novel features of the invention will be apparent from the following description taken in connection with the accompanying 25 drawings, in which:

Figure 1 is a longitudinal section of a two stage pump. Fig. 2 is a transverse section on the line 2—2 of Fig. 1. Fig. 3 is a side view of one of the casing sections showing 30 the radially arranged water passages.

Referring to the drawings the numeral 10 indicates the pump shaft which has mounted thereon the runners or rotors 11 and 12. The pump is provided with bearings 13 and 14 for the shaft 10 and the latter is provided with a coupling 15 for the purpose of connecting the pump with any suitable source of power. The pump casing comprises the inlet cover 16 which is provided with the inlet 17, and a discharge cover 18 having an outlet 19. Between the covers 16 and 18 is arranged an intermediate section 20. The cover 16 is provided with a sleeve 21 which surrounds the hub of the 40 runner 11 and makes a close fit therewith to prevent the leakage of water past the runner. The cover 16 is also provided with vanes 22 forming the diffusion passages 23 which receive the water from the runner 11. 45 These vanes are integrally formed with the cover 16 and abut the side of the disk 24, which has formed on its opposite side the channels or passages 25 connecting with the diffusing passages by a return bend 26 adjacent the periphery of the casing. The pas-

sages 25 are separated by the vanes 27 which are formed integrally with the disk 24 and abut the smooth surface of the intermediate section 20. The cover 16 is also provided with a recess 28 which receives the ring 29 forming one side of the return bend 26. 60 Adjacent the shaft 10 the intermediate section 20 is provided with a sleeve 30 similar to the sleeve 21 above described and adapted to prevent leakage past the runner 12. 65 The section 20 has formed on one side thereof the diffusing passages 31 which receive the discharge from the runner 12. These diffusing passages are similar to the passages 23 and the construction of this side of the 70 intermediate section 20 is similar to that of the cover 16. The vanes forming the passages 31 abut the smooth surface of the disk 32 which is also provided with vanes and passages for delivering water to the 75 discharge chamber 19 which is formed between the disk 32 and the cover 18. The cover 18 has a smooth inner surface which abuts the vanes on the disk 32. A ring 33, 80 similar to ring 29, is provided between the intermediate section 20 and the cover 18 for the purpose of forming one side of the return bend which connects the passages 31 with the outlet 19. As thus constructed it will be seen that the inner surface of the 85 cover 18 is perfectly smooth and may be turned in a lathe. The left hand side of the intermediate section 20 also has a smooth surface which may be turned in a lathe, and by reference to Fig. 3 it will be seen that the 90 passages 25 formed between the vanes 27 on the disk 24 may be readily machined.

In order to enable the construction to be more readily understood the vanes have been shown as slightly separated from the adjoining surfaces, but it will be understood that this is not the way the construction will be carried out in practice, the vanes being arranged to fit closely against these surfaces. The sections are bolted together by bolts 33 95 which clamp the intermediate section between the covers. It will be understood that the same construction will be followed out in a pump having three or four, or more stages, the construction for the other stages 100 being similar to that shown and described.

Having thus described my invention what I claim is:

A multi-stage turbine pump comprising a shaft, a plurality of runners mounted on 110

said shaft and having axially arranged inlets, and a casing inclosing said runners and provided with passages leading from the periphery of one runner to the inlet of the next runner and including a return bend adjacent the periphery of the casing, said casing being formed in sections which are separable on planes through said water passages and having rings arranged between the sec-

tions and adapted to form one side of said 10 return bends.

In testimony whereof I affix my signature in presence of two witnesses.

WILLIAM A. DOBLE.
